UNITED STATES PATENT OFFICE.

MICHAEL RADAKOVICH, OF MILWAUKEE, WISCONSIN.

PROJECTILE.

1,343,747.

Specification of Letters Patent. Patented June 15, 1920.

Application filed October 25, 1918. Serial No. 259,709.

To all whom it may concern:

Be it known that I, MICHAEL RADAKOVICH, a citizen of the United States, residing at Milwaukee, county of Milwaukee, and State 5 of Wisconsin, have invented new and useful Improvements in Projectiles, of which the following is a specification.

My invention relates to improvements in high explosive shells.

10 My invention has for its primary object to provide means whereby a plurality of shells arranged in series, (preferably a pair of shells in tandem), can be discharged from a shell containing a propelling charge, 15 and the shells thus discharged held in spaced relation to each other during their flight toward the objective at which they are aimed. The series of shells may comprise shells of differing character, although each 20 will preferably contain a high explosive charge. It is a part of my object to employ at least one shell which will explode on contact with the objective, and another shell containing a time fuse, whereby this shell 25 may be exploded within a definite time interval after it has been fired.

Another object of my invention is to utilize the means for connecting the high explosive shells to also hold them in spaced 30 relation to each other within the main cartridge or shell which contains the propelling charge, whereby concussion of the shells upon each other in such a manner as to detonate the charges may be avoided.

35 In the drawings:—

Figure 1 is an elevation, partly in section, of a device embodying my invention.

Fig. 2 is an elevation of the shells containing the high explosive charge, as they 40 appear during their flight through the air.

Fig. 3 is a view similar to Fig. 1, showing a modified form of construction, and

Fig. 4 shows the high explosive shells of the Fig. 3 type during their flight through 45 the air.

Fig. 5 is an end view of the inner high explosive shell illustrated in Fig. 3.

Like parts are identified by the same reference characters throughout the several 50 views.

In Fig. 1, the cartridge comprises a tubular shell 1, provided with a propelling charge 2 in the rear end portion of the cartridge, this end being closed as in any ordinary cartridge. A high explosive shell 3 is

located within this cartridge shell 1, in front of the propelling charge, and preferably contains a time fuse, whereby it will be exploded within a definite time interval after it has been fired. Another high explosive shell 5 is mounted in the open end of the shell 1, with its base in substantial contact with the nose 7 of the shell 3. The interior of the shell 3 is provided with a passage 9 containing a plunger 10. The 60 passage extends for some distance within the shell along a line parallel with the axis thereof, and is then elbowed, and extends through the wall of the shell, communicating with a channel 12 along the side of 65 the shell, and extending along a helical line 13 about the nose thereof. The forward high explosive shell 5 is provided with a similar passage 13 elbowed at 14, and communicating with a rearwardly extending 70 surface channel at 15, leading along the side of the shell parallel with the axis and through the base thereof.

A wire cable 17 connects the plunger 10 with a corresponding plunger 20, located in 80 the passage 13, this cable extending from the plunger 10 along the passage 9 to the exterior, and then along the channels 12 and 13 to the opposite side of the shell, where it enters the channel 15, and passes into the 85 passage 13 to its point of connection with the plunger 20. The portion of the cable contained within the channels 12 and 15 will be inclosed by the walls of the outer or container shell 1, and this will have a tendency to hold these two shells in spaced 90 relation to each other, while the shells are within the outer container and prevent excessive pressure by the rear shell 3 upon the base of the forward shell, but as soon as 95 the shells leave the muzzle of the gun, the air resistance will have a tendency to separate them, and during the final portion of the flight of the shell they will tend to assume the position in which they are illustrated in Fig. 2, although not necessarily parallel with each other, since one may be still somewhat in advance of the other.

It will, of course, be understood that owing to the fact that the two shells are connected with each other, the connection will also serve as an agent of destruction during flight. As soon as one of the shells explodes the other shell will be released, and in view of the fact that the contact fuse 100 110

regulates one explosion, whereas the time fuse regulates the other, the two shells will not ordinarily explode simultaneously.

Referring now to Figs. 3, 4, and 5, it will be observed that the construction is similar to that disclosed in Figs. 1 and 2, the outer shell 1^a being the same in form, and inclosing the propelling charge 2^a. In this construction also, two high explosive shells 3^a and 5^a are arranged in tandem, but instead of connecting them by the cable, as disclosed in Figs. 1 and 2, I connect them by a set of rods 25 and 26, one rod 26 being preferably located along the central axis common to the two shells, within a tube 28 prepared for that purpose. A plurality of rods 25 are grouped around this centrally disposed rod, and all of the rods may be provided with plungers or piston shaped members 30 and 31 on their extremities.

In this construction, the two shells will travel to their destination in tandem, the rods extending longitudinally, and there being no tendency for the air to catch in exterior grooves, as is the case in the construction shown in Fig. 1. The advantage of the tandem arrangement is that the shells will carry farther than with the arrangement illustrated in Figs. 1 and 2, each shell being smooth surfaced, and the connecting rods between the two meeting with slight air resistance. These rods practically travel in a vacuum. Therefore, for long ranges, I prefer the construction shown in Figs. 3 and 4, whereas for short ranges the construction shown in Figs. 1 and 2 is preferred, because of the additional destructive effect produced by the transversely disposed connecting cable. The rods also serve as spacers more effectually than does the cable, shown in Fig. 1, during the time that the shells are being fired, *i. e.*, during the expansion of the charge 2^a. At this time the ends of the rods are at the extremities of the tubular passages, or cavities, prepared in their respective shells to receive them.

It will be understood that by providing one of the shells with a contact fuse, and the other with a time fuse, the shell with the contact fuse will, of course, explode upon impact, and inasmuch as the two shells are connected, the force of the explosion will necessarily drive the other shell away from the point where the first explosion takes place, the shell with the time fuse exploding therefore at a point which has not been devastated by the explosion of the first shell. Further, it is obvious that if the condition

of the ground, by reason of moisture or otherwise, should be such that the contact shell failed to explode, the other would not be affected by the condition of the ground, but would explode at the expiration of the period of time determined by the time fuse. This explosion would, of course, tend to also explode the contact shell.

In this construction as in that shown in Figs. 1 and 2, I preferably make one of the high explosive shells with a time fuse, and the other with a contact fuse, the one with the contact fuse being preferably located in advance of the other one.

I claim:—

1. A projectile comprising the combination with a set of high explosive shells, of a spacing connection between the shells having its end portions anchored within the rear portions of the respective shells, each shell being provided with an elongated interior chamber within which the anchorage portion of the flexible connection may slide to allow the shells to separate from each other to a distance equal to the sliding movements of the anchorage members after the shells have been discharged from the gun. 80

2. A projectile comprising the combination with a set of high explosive shells, each provided with an elongated chamber in its rear portion, and a flexible spacing member having enlarged end portions slidably anchored in said elongated chambers, and adapted to allow the shells to be fired from a gun with the spacing member substantially inclosed within the shells while allowing the shells to separate in the air at a distance equal to the movements of the anchorage members within their respective chambers. 90

3. A projectile, comprising the combination of a set of high explosive shells, one provided with a contact fuse and the other with a time fuse, and a spacing connection between the two shells. 100

4. A projectile, comprising the combination of a set of high explosive shells, one provided with a contact fuse and the other with a time fuse, and a spacing connection between the two shells, composed of a flexible member slidably connected with the respective shells. 110

In testimony whereof I affix my signature in the presence of two witnesses.

MICHAEL RADAKOVICH.
